UNITED STATES PATENT OFFICE

FRANK C. MARQUARDT, OF BROOKLYN, NEW YORK, ASSIGNOR TO AMERICAN BANK
NOTE COMPANY, OF NEW YORK, N. Y., A CORPORATION OF NEW YORK

INK MIXER

Application filed December 19, 1930. Serial No. 503,381.

My invention relates to an ink mixer, and more particularly to improvements by which the pigments and the vehicle forming the ink may be subjected to a continued, uniform stirring action without likelihood of such variation in the working conditions of the machine as would interfere with the quality of the ink due to variation in the action of the different mechanisms upon or in the time interval during which, the ingredients of the ink are subjected to the stirring and mixing action of the different parts of the machine.

In the production of ink for high grade printing purposes, expensive pigments and expensive oils as a vehicle are used. The oil and the pigments are delivered to a circular tub or can which, during the mixing operation, is rotated at low speed. Co-operating with the tub or can is a rotatable head carrying a plurality of paddle blades positioned within the tub or can. The axis of rotation of said head carrying the paddles is eccentric to the axis of the tub or can, so that in their rotation, the paddles or blades act upon the oil and pigment adjacent the side of the tub or can and the center thereof. Hence, with each rotation of the tub or can, the entire contents thereof are successively brought within the operative range of said paddles.

In the mixing of such inks, to avoid spoilage thereof, the time interval of the mixing operation should not be extended beyond that which is required to bring the ink to a desired condition suitable for its use in a press. If this interval be too long, the ink will not have the desired consistency, and this is also true if the interval be too short. Furthermore, all parts of the ingredients in a batch should be mixed in as nearly the same manner as is possible.

In order to enable the operator to produce ink of the desired quality, it is essential that the ingredients in the tub or can be subjected to the action of the paddles at a uniform speed for a definite time interval.

Heretofore, mixing machines have been used which embody therein a bevel gear for rotating a turn-table supporting a tub or can, a bevel gear for rotating a paddle head and a single power driven wide bevel gear en-

meshed with both of said other gears. With this construction, the bevel gears driving both the turn-table for the tub or can and the paddle head, was subject to complex stresses which resulted in excessive wear as to the portion thereof actuating the paddle head, so that after the mixer had been in use a short time, there was constant likelihood of variation in the actuation of the paddle head and breakage of the gearing driving same. This might occur at any time, even while a batch of the ink was being mixed, so that the continuity in the mixing operation would have to be interrupted to effect repairs. The interruption in the mixing operation not only reduced the production capacity of the machine, but might lead to such under or over-working of the ink in the tub or can as to impair the quality of the ink, even to the point of making it unsuitable for use in the inking mechanism of printing machines. Furthermore, variation in the speed of operation of the paddles had the effect of subjecting different portions of the ink in the tub or can to a variable working which also had its effect in the quality of the ink.

With the above conditions in mind, I have provided a mixing machine the mechanisms of which are so constructed and arranged as to ensure continued, uniform movement of the paddle blades and of the turn-table for the tub or can in relation to each other. The various parts are so constructed as to ensure a desired timing in the movements of the paddles and of the turn-table for the tub or can, and the maintenance of this timing with a long continued use of the machine.

In securing this result, I employ independent bevel gears co-operating respectively with the bevel gear carried by the turn-table and the bevel gear carried by the paddle head, the pitch diameters of these gears being determined by the axis of rotation of said paddle head and of said turn-table respectively. Both gears are simultaneously actuated from the main driving shaft through a speed reducing gearing, the power applied to which is preferably derived from an electric motor.

With the construction of a machine embodying the invention, a proper time interval for securing the desired quality of the ink may be predetermined with the assurance that with a continued operation of the machine different batches of ink will have substantially the same quality, thus in large measure avoiding the exercise of the judgment of the operator in determining when the pigment and oils have been properly treated. Furthermore, reliability in the operation of the machine permits it to be operated with the minimum of attention.

The invention consists primarily in an ink mixer embodying therein a turn-table adapted to receive a tub or can, a bevel gear carried thereby having a pitch determined by the axis of rotation of said turn-table a rotatable paddle head, the axis of which is eccentric to the axis of said turn-table, a bevel gear carried thereby of relatively smaller diameter than the bevel gear carried by said turn-table, the pitch of said gear being determined by the axis of rotation of said head, a shaft, a plurality of bevel gears carried thereby and enmeshed respectively with the gear carried by said turn-table, and with the gear carried by said paddle, the pitch of the gear enmeshed with the gear carried by the turn-table being determined by the axis of rotation of said turn-table, and the pitch of the other of said gears being determined by the axis of rotation of said head, and speed reducing gearing operative upon said shaft; and in such other novel features of construction and combination of parts as are hereinafter set forth and described, and more particularly pointed out in the claims hereto appended.

Referring to the drawing,

Fig 1 is a side view of an ink mixer embodying the invention; and

Fig. 2 is a plan view thereof.

Like numerals refer to like parts in both of said views.

In the embodiment of the invention shown in the drawing the main frame of the machine 10 has mounted, in an extension thereof, a turn-table 11 supported adjacent its periphery by roller bearings 13 and carrying a large bevel gear 12. The pitch surface of this gear is determined by the axis of the turn-table 11. A tub or can 14 is removably mounted upon the turn-table 11 in a manner to be rotated with said table. Carried by the main frame 10 are vertically extending guideways 15 having associated therewith a vertically extending rack 16. The guideways 15 and rack 16 are supported by a hollow upright 17 at the top of which are guide pulleys 18.

Mounted in the guideways 15 is a paddle head 19 in which is rotatably mounted a shaft 20 carrying a bevel gear 21, the pitch surface of which is determined by the axis of

the shaft 20. Also carried by the shaft 20 is a plate 21a to which is secured a plurality of paddle blades 22 of a length to reach closely adjacent the bottom of the tub or can 14 when the paddle head 19 is in its lowermost position.

The axis of the shaft 20 is eccentric to the axis of turn-table 11 to an extent to bring the paddle blades during their rotation, closely adjacent the side of the tub or can and closely adjacent the axis of rotation of the turn-table 11, thus causing said paddles to act upon the contents of the tub or can between the side of the tub or can and the axis of its rotation.

Connected with the head 19 is a flexible connection 23 passing over the pulleys 18 and connected with a counterweight 24 movable in the hollow upright 17. Mounted in the paddle head 19 is a shaft 25 carrying a gear 26 enmeshed with the rack 16, and a hand wheel 27. The shaft 25, gear 26 and hand wheel 27 afford means by which the paddle head 19 may be raised or lowered in relation to the turn-table 11 and the tub or can 14 carried thereby.

Also carried by the shaft 25 is a ratchet wheel 28 cooperating with which is a dog 29 for preventing a return movement of the head 19 and parts appurtenant thereto when this head has been elevated. Said ratchet and dog may be used to sustain the head 19 when the paddle blades 22 have been lowered to the desired extent.

Mounted in the frame 10 is a shaft 30 carrying a bevel gear 31, the pitch surface of which corresponds with that of the gear 12. Driven from said shaft is a second and smaller gear 32, the pitch surface of which corresponds with that of the gear 21. The gear 32 is made entirely independently of the gear 31 and is secured thereto and to the shaft 30 in any desired manner as by means of the bolts 33 passing through the gear 32 and engaging the gear 31.

In the form of the invention shown, the actuating power is derived from an electric motor 34, there being positioned between this and the shaft 32 a speed reducing mechanism consisting of the entrained gears 35 and 36 driving the shaft 37, the power from which shaft is applied to the shaft 30 by means of the entrained gears 38 and 39.

The pitch of the gear 31 is determined from the axis of rotation of the turn-table 11, while the pitch of the gear 32 is determined by the axis of rotation of the shaft 20.

The operation of the herein described machine is substantially as follows:—

Before placing a batch of pigment and oil in the tub or can 14, the hand wheel 27 is used to turn the gear 26, the cooperation of which gear with the rack 16 raises the paddle head 19 so as to bring the paddle blades 22 above the top of the can to an extent to per-

mit free access thereto. When the batch is in the can, said mechanisms are again used to lower the paddle blades until the bottom of said blades are closely adjacent the bottom of the tub or can 14.

When the parts are so positioned, power is applied to the motor 34 which, through the speed reducing gearing, will impart rotary movement to the turn-table 11 and to the paddle head 19. The number of revolutions per minute of the paddle head is relatively greater than those of the turn-table 11, so that the mixing action is a local stirring action by the paddles 22, which is progressively extended to all of the batch in the tub or can as a result of the turning of the turn-table 11 and the tub or can 14 carried thereby. This action, however, is limited to the material upon one side of the axis of rotation of said turn-table.

While the machine is in operation, both the turn-table and the paddles operate continuously without any appreciable variation in their speeds, thus ensuring a uniform stirring action throughout all of the contents of the tub or can as it is brought within the operative range of the paddles. By reason of the construction and arrangement of the various gears, this constant, uniform speed is maintained throughout the entire period required for properly mixing the ink. The result of this continuous, even stirring action is the bringing of every portion of the batch to a desired uniform condition. Furthermore, the mechanisms employed avoid any possibility of the interruption of the action of the paddles due to excessive wear or mutilation of the gears driving same.

Stoppage of the machine, when the mixing operation is once started and before it is completed, is undesirable, since the interruption of the mixing operation may result in a variation of the time interval to an extent to seriously impair the quality of the finished product. The effect of such stoppage will vary according to the stage in the mixing of the ink at which the stoppage occurs.

The main object of the invention is to permit a continuous, uniform operation of the machine during the entire period required to properly mix the ink, and the mechanisms employed are for the purpose of avoiding conditions which may result in accidental stoppages or fluctuation in the speed of operation of the machine.

With the construction and arrangement of gearing described, the gears are subjected to very little wear and there is little or no likelihood of binding or breaking of gears which might result in variation of the speed or stoppage of the machine.

With the machine of the invention it is possible to mix succeeding batches of pigment and vehicle with the assurance that all of the ink thus produced will be in substantially the

same condition, since the same time interval will cause every portion of each batch to be subjected to the action of the paddles under exactly the same conditions.

The inks produced in the machine of the invention are highly viscous, and if not properly worked develop properties which will make them unsuited for use in the type of printing machine with which such inks are used. There is little or no tendency of the mixed inks to flow, and this is relied upon in the final stages of the mixing action.

When a batch of ink has been properly worked in the mixer, the paddle head 19 is elevated, the ink cleaned from the paddles thereof and the tub or can 14 removed from the turn-table 11. If pigments of the same color are to be used in the next batch, a fresh tub or can is mounted upon the turn-table 11 and the operations above referred to are repeated with this batch. If pigments of different colors are to be used, of course it is necessary to thoroughly clean the paddles.

The certainty of operation of the machine not only results in uniformity in the quality of the product over a long run of the machine, but a material saving in the maintenance of the machine, the material used in the different batches and the labor required to operate the machine. It is possible, with the machine of the invention, to rely upon the time interval during which the machine is operative as to each batch to secure the desired product, and to depend less upon the acquired skill of the operator in determining by observation when the ink is approaching a proper condition.

It is not my intention to limit the invention to the precise details of construction shown in the drawing, it being apparent that such may be varied without departing from the spirit and scope of the invention.

Having described the invention, what I claim as new and desire to have protected by Letters Patent, is:

1. An ink mixer embodying therein a turn-table adapted to receive a tub or can, a bevel gear carried thereby having a pitch determined by the axis of rotation of said turn-table, vertically extending guideways, a vertically extending rack adjacent said guideways, a paddle head slidably mounted in said guideways, a gear wheel carried thereby cooperating with said rack, a holdback mechanism operative upon said gear, means whereby said gear may be turned, a shaft rotatably mounted in said head, the axis which is eccentric to the axis of said turn-table, a plate carried by said shaft, a plurality of paddle blades carried by said plate and of a length to reach closely adjacent the bottom of a tub or can upon said turn-table, a bevel gear carried by said shaft of a relatively smaller diameter than the bevel gear carried by said turn-table, the pitch of said gear being determined

by the axis of rotation of said plate, a shaft, a plurality of bevel gears carried thereby and enmeshed respectively with the gear carried by said turn-table, and with the gear carried by said shaft, the pitch of the gear enmeshed with the gear carried by the turn-table being determined by the axis of rotation of said turn-table, and the pitch of the other of said gears being determined by the axis of rotation of said paddles, and speed reducing gearing operative upon said shaft.

2. An ink mixer embodying therein a turn-table adapted to receive a tub or can, a bevel gear carried thereby having a pitch determined by the axis of rotation of said turn-table, vertically extending guideways, a vertically extending rack, adjacent said guideways, a paddle-head slidably mounted in said guideways, a gear wheel carried thereby cooperating with said rack, a holdback mechanism operative upon said gear, means whereby said gear may be turned, a shaft rotatably mounted in said head, the axis which is eccentric to the axis of said turn-table, a plate carried by said shaft, a plurality of paddle blades carried by said plate and of a length to reach closely adjacent the bottom of a tub or can upon said turn-table, a bevel gear carried by said shaft of a relatively smaller diameter than the bevel gear carried by said turn-table, the pitch of said gear being determined by the axis of rotation of said plate, a shaft, a plurality of bevel gears carried thereby and enmeshed respectively with the gear carried by said turn-table, and with the gear carried by said shaft, the pitch of the gear enmeshed with the gear carried by the turn-table being determined by the axis of rotation of said turn-table, and the pitch of the other of said gears being determined by the axis of rotation of said paddles, a large gear carried by said shaft, a second shaft having a small gear carried thereby entrained with said large gear, a source of power, a small gear driven thereby and a large gear carried by said last named shaft entrained with said last named smaller gear.

In witness whereof I have hereunto affixed my signature, this 12th day of December, 1930.

FRANK C. MARQUARDT.
